UNITED STATES PATENT OFFICE.

ROBERT H. PALM AND WILLIAM F. POHLMANN, OF CHICAGO, ILLINOIS, ASSIGNEES TO
F. W. MATEER & CO., OF CHICAGO, ILLINOIS, A CORPORATION OF ILLINOIS.

SAFETY DEVICE FOR LAUNDRY MACHINES.

Application filed April 3, 1925. Serial No. 20,575.

The invention has general reference to power driven laundry machinery, and is especially applicable to machines of the type embodying a receptacle having a suitable closure and operating mechanism in the receptacle driven by the application of motive power through the medium of a power transmission including a movable control element.

The primary object of our invention is to provide, in a machine of the character indicated, means which will insure that the cover or closure can not be opened when the machine is in operation, and that when the cover is open, the power transmission control is inoperative to set the operating mechanism in motion.

An important feature of the mechanism which we have devised for carrying out the object thus set forth is an interlocking mechanism comprising a pair of stop members which, when the machine is in operation, occupy a relation such as to prevent the cover from being opened, and a third stop member which, when the cover is open, is locked by said pair of members in a position to prevent the operation of the control element of the power transmission to set the machine in motion. Another feature is the provision of a locking means for said interlocking mechanism, capable of manipulation to release the interlocking mechanism and the cover held thereby only when the machine is at rest.

A general object of our invention is to provide a safety means of the character indicated which is relatively simple in construction and in operation, and is otherwise of a practical character.

For purposes of illustration, we have shown and will hereinafter describe our invention as applied to a power driven washing machine, but it will be apparent that in its broader aspects the invention is capable of application to other power driven laundry machines. Moreover, it is contemplated that various changes in the construction and arrangement set forth may be made by those skilled in the art without departing from the spirit and scope of the invention as expressed in the appended claims.

In the drawings Figure 1 is a side elevational view of a washing machine having our invention applied thereto.

Fig. 2 is an end view of the same.

Fig. 3 is a fragmentary plan view show-

ing one relation of the pair of stop members forming part of the interlocking mechanism.

Fig. 4 is a fragmentary side elevational view illustrating the third stop member in relation to the control element of the power transmission different from that shown in Fig. 2.

Figs. 5 and 6 are fragmentary vertical sectional views through a portion of the locking means for the interlocking mechanism and illustrating the method of operation in releasing the lock to permit operation of the interlocking mechanism.

Fig. 7 is a fragmentary plan view of the end of the machine shown in Fig. 2.

Fig. 8 is a fragmentary vertical sectional view taken approximately in the line 8—8 of Fig. 9.

Fig. 9 is a fragmentary transverse sectional view taken approximately in the plane of line 9—9 of Fig. 8.

The washing machine selected for purposes of illustration comprises a cylindrical body 10 supported at opposite ends by frame members 11 and 11^a and having an opening 12 therein near its upper forward side arranged to be closed by a sliding cover 13. The body 10 serves to enclose the usual cylinder 10^a arranged to be driven first in one direction and then in the other by the application of motive power through the medium of the power transmission which in the present instance consists of a plurality of pulleys 14, 15 and 16. The pulleys 14 and 15 are mounted loosely on a shaft 17 geared to the rotary cylinder and the pulley 16 is located between the pulleys 14 and 15 and is made fast upon said shaft 17. We have shown in broken lines in Fig. 1 a pair of belts 18 and 19 running over the pulleys 14 and 15 respectively and connected with a suitable source of power as, for example, an overhead drive shaft (not shown). The belt 18 is shown as being twisted so as to drive the pulley 14 in a direction opposite to that in which the pulley 15 is driven.

The power transmission as shown further embodies the reversing mechanism comprising a bar 20 mounted in an upstanding bracket 21 for reciprocation in a direction parallel to the axis of the shaft 17. Said bar carries at opposite sides thereof (Fig. 7) a pair of belt shifters or guides 22 and 23 overlying respectively the pulleys 14 and 110

15. Slidable relative to the bar 20 and depending therefrom is a plate 24 having opposed cam surfaces 25 and 26 (Figs. 8 and 9) arranged to be engaged by a projection 27 on a worm wheel 28 suitably journaled in the bracket 21. The worm 28 is arranged to be continuously driven from a worm 29 journaled on the shaft 17 and having a clutch connection at all times with the pulley 15. The latter is constantly driven by the belt 19 which, as indicated in Fig. 1, is of a width such that even when shifted onto the tight pulley 16 it overlaps the loose pulley 15. It will be seen that the rotation of the worm wheel and, together therewith, the cam members 25 and 26, serves to reciprocate the plate 24 and thereby the slide rod 20 carrying the belt shifter guides 22 and 23, thus alternately connecting the pulleys 14 and 15 with the tight pulley 16 for the purpose of rotating the washing cylinder in one direction or the other.

The connection between the plate 24 and the belt shifter bar 20 comprises a rocker member 30 pivotally mounted on the bar 20 through the medium of a bracket 31 (Fig. 8) and adapted to enter a notch 32 formed in the upper end of the plate 24 as shown in Figs. 1 and 9. When the rocker member 30 is moved upwardly from the position shown in Fig. 9 to disengage it from the notch 32, the power transmission is inoperative. To lock said mechanism against operation, the rocker member 30 is swung rearwardly as shown in Fig. 4 in which position it engages in a notch 33 formed in the upper end of the member 34 fixed upon the bracket 21 (Fig. 9).

It will thus be apparent that the rocker member 30 constitutes the control element of the power transmission; that when it occupies the operative position shown in Fig. 9 the belt shifter guides are reciprocated through the continuous operation of the reversing mechanism; and that when the element is in the inoperative position shown in Fig. 4, the belts in this position run on the loose pulleys 14 and 15.

The safety means which we have provided is operatively associated with the cover 13 and with the rocker member or control element 30. It comprises a pair of interlocking stop members 35 and 36 adapted when in one relation to prevent the cover 13 from being opened. When in another relation, with the cover in open position, a third stop member 37 is held in a position to lock the control element 30 in its rearward or inoperative position (Fig. 4). The locking mechanism generally designated by the numeral 38 (Fig. 2) has the stop members 35 and 37 directly connected thereto for movement respectively into and out of the paths of movement of the stop member 36 and the control element 30, and said locking mech-

anism is associated with the main shaft 17 in a manner such that when this shaft is in operation the locking mechanism is incapable of manipulation to move the stop members 35 and 37.

The stop member 35 is in the form of a segmental plate (Fig. 7) and is fast upon the upper end of a vertical rock shaft 39 journaled at opposite ends in bearings provided by an upright bracket 40 secured to the end 70 frame member 11. Said bracket is shown in Fig. 1 as shaped to enclose a device generally designated by the numeral 41 for adjusting the inner cylinder with reference to the body 10 so as to bring the covers in 75 registering relation. Since this device forms no part of our invention, it need not be described in detail.

The stop member 36 is mounted to turn with a horizontal rock shaft 42 (Figs. 1, 85 2 and 7) mounted in bearing members 43 on the upper ends of the two frame members 11 and 11^a and having a connection between its ends with the door 13. This connection 90 comprises in the present instance a lever arm 44 fast upon the shaft 42 and connected with the slide door 13 by means of a link 45 and an angle bar 45^a rigid therewith. The arrangement is such that when the cover 13 is in its closed position the two members 35 and 36 occupy the relation shown in 95 Figs. 2 and 7 in which member 35 overlies the member 36 so as to prevent the opening of the cover.

The stop member 37 is mounted to turn on an axis parallel to the shaft 42 but somewhat below it. As shown in Fig. 7, this member is carried on the outer end of an arm 47 pivoted at 48 on the rear end of an arm 49 adjustably supported on the bracket 40. The arm 47 is pivotally connected at 47^a eccentrically of its fulcrum 48 with the vertical shaft 39 through the medium of an adjustable link 50 which in turn is pivoted to a crank arm 51 on said vertical shaft 39. The arrangement in this instance is such that when the shaft 39 is rotated to swing the stop member 35 out of the path of movement of the stop member 36 so as to permit the opening movement of the cover, the stop member 37 swings downwardly into the path 110 of movement of the control element 30 as shown in Fig. 4.

However, before the shaft 39 may thus be rotated, it is essential that the machine be first brought to rest through the operation of the control element into its inoperative position shown in Fig. 4; and also as a condition precedent to this operation, the locking mechanism 38 must be adjusted by the operator to release the shaft 39, which may be accomplished by reason of the cessation of the rotation of the shaft 17.

The locking mechanism 38 comprises (Figs. 2, 5 and 6) a hollow casing or drum

52 mounted coaxially of a shaft 17^a carrying the rotor 10^a, and having a hole 54 in its periphery disposed midway between a pair of shoulders 55 and 56. A bifurcated member 57 has a frictional driving connection with the shaft 17^a accomplished in the present instance by means of a split collar 58 rigid with the member 57 and having lugs 59 connected by a bolt 60 which is encircled by a spring 61 acting to hold the collar in frictional contact with the shaft 17^a. A rod 62 slidably supported in a bracket 63 on the main bracket 40 (Figs. 1 and 2) has a pin 64 rigid therewith which is adapted to enter the hole 54 in the casing 52 when the latter is positioned opposite (Fig. 5), and also to enter a notch 65 formed in the member 57 when the latter is positioned opposite the hole 54 (Fig. 6). A pair of lugs 66 on the periphery of the casing 52 and equidistantly spaced on opposite sides of the hole 54 serve to limit rotary motion of the casing by contact with the pin 64, the casing being provided with a handle 67 to facilitate adjusting the parts. By reason of the frictional contact between the member 57 and the shaft 17^a, the former, in the rotation of the shaft in one direction or the other moves into engagement with one or the other of the shoulders 55 and 56 depending upon the direction of rotation. Thereupon the member 57 is held stationary, and upon a cessation in the rotation of the shaft, it is possible by rotating the casing 52 in a direction opposite that in which the shaft has been rotating, until one of the lugs 66 strikes the pin 64 which will serve to carry the notch 65 of the member 57 into a position opposite the pin 64. It then remains to reverse the direction of rotation of casing 52 slightly to position the hole 54 opposite the pin 64 whereupon the pin may be moved through the hole and into the notch 65. In such movement the rod 62 is operated. By reason of a link connection 68 between the rod 62 and a crank arm 69 on the vertical shaft 39 the latter will be rocked in a direction such as to carry the stop member 35 out of the path of movement of the stop member 36, and the stop member 37 will be moved into the path of movement of the control element 30. The stop member 37 thus serves to lock the control element in its inoperative position while the door 13 may be slid open unrestricted by the stop member 35.

The stop member 35 now occupies a position on the inner side of the stop member 36 so that the latter prevents a reverse rotation of the shaft 39 and hence the movement of the stop member 37 into a position such as to permit the control element 30 to be moved into its forward or operating position so long as the door remains open.

It will thus be seen that we have provided means effectually insuring that when the

machine is in operation the cover or door of the body 10 cannot be opened by the operator with a possible resulting injury to him; and that when the machine has been brought to rest and the cover opened it cannot be restarted until the cover or door has been moved into closed position. Moreover, we have provided locking means for the interlocking mechanism of a character such that before the interlocking mechanism can be operated to render it possible either to open the door or to release the control element, the machine must be at rest.

We claim as our invention:

1. In a machine of the character described, the combination of a body having a closure, a part mounted to turn on a horizontal axis and connected with said closure for movement therewith, a stop member mounted to turn on a vertical axis for movement into and out of the path of movement of said part, and means for swinging said stop member.

2. In a machine of the character described, the combination of a body having a closure and containing an element to be driven, a part operatively connected with said closure for movement therewith, a swingable stop member, said part and said stop member being mounted on axes substantially perpendicular to each other, and means for swinging said stop member into and out of the path of movement of said part comprising a rock shaft, and a device operatively associated with the element to be driven and adapted for actuation when said element is at rest to lock said shaft.

3. In a machine of the character described, the combination of a body having a closure and containing an element to be driven, a part operatively connected with said closure for movement therewith, a swingable stop member, said part and said stop member being mounted on axes substantially perpendicular to each other, and means for swinging said stop member into and out of the path of movement of said part comprising an operating rod operatively connected with said member and mounted for axial movement, means automatically positioned in the rotation of said element to prevent operation of said movable rod but adapted to be adjusted when the driven element is at rest to permit movement of said rod whereby to rock said member.

4. In a machine of the character described, the combination of a driven element, a part to be moved, means for locking said part against movement, and means operatively associated with said driven element for locking the last mentioned means in locking position comprising a pair of members each adapted to be moved in the rotation of said driven element, a third

member normally held against movement by said pair of members, and means for adjusting the pair of members when the driven element is at rest to permit movement of said third member.

5. In a machine of the character described, the combination of a driven element, a part to be moved, means operable to hold said part against movement, and a locking means comprising a member operatively connected with the first mentioned means and a pair of members adapted to be relatively positioned in the rotation of said driven element so as to prevent the movement of said first member but adjustable when the driven element is at rest into position to permit movement of the first member.

6. In a machine of the character described, the combination with a part to be moved, of a driven element, and a locking mechanism including a member operatively associated with the part to be moved, two concentrically arranged members arranged to be moved by the driven element in its rotation into a position such as to prevent movement of the first member, and means for adjusting said pair of members when the driven element is at rest whereby to permit movement of the first member.

7. The combination with a machine of the character described of a part to be moved, a locking means for said part comprising, in combination with a driven shaft, a casing mounted for limited rotational movement by said shaft, a member in the casing also mounted for limited rotation therewith, a second member associated with the part to be locked, said casing and member therein being adjustable when the driven element is at rest into a position to permit movement of the second member.

8. A machine of the character described having a movable part and a locking mechanism therefor comprising, in combination with a driven shaft, a casing having an opening therein on said shaft, a member in said casing arranged to be moved by said shaft, a second member adapted for movement into and out of said opening in said casing, said first member being adapted normally to prevent movement of said second member through said opening, and means for adjusting said first member to permit of such movement of said second member.

9. In a machine of the character described, a safety device comprising, in combination with a driven element, operating means, a locking means comprising a stop member arranged to be moved by said element, a member operatively associated with said operating means and adapted normally to be held against movement by said stop member, and means for adjusting said stop member to permit of such movement comprising a casing enclosing said stop member and having

an opening therein to receive the other member, said stop member being adjustable in the movements of said casing.

10. In a machine of the character described, a safety device comprising, in combination with a driven element, operating means, a locking means comprising a stop member arranged to be moved by said element, a member operatively associated with said operating means and adapted normally to be held against movement by said stop member, and means for adjusting said stop member to permit of such movement comprising a casing enclosing the stop member and having an opening therein to receive the other member, said stop member being adjustable in the movements of said casing, and means for limiting the rotational movement of said casing relative to said other member.

11. In a machine of the character described, a safety device comprising, in combination with a driven element, operating means, a locking means comprising a stop member arranged to be moved by said element, a member operatively associated with said operating means and adapted normally to be held against movement by said stop member, and means for adjusting said stop member to permit of such movement comprising a casing enclosing the stop member and having an opening therein to receive the other member, said stop member being adjustable in the movements of said casing, and said casing and said stop member being frictionally driven by said driven element.

12. A machine of the character described having a safety device comprising, in combination with a driven element, operating means including a movable pin, a casing on said driven element and having an aperture, and a bifurcated member in the casing and having a frictional driving connection with the driven element, said casing and said member being adapted to receive said pin when said aperture and the space between the bifurcations of said member are in registering relation opposite said pin.

13. A machine of the character described having a safety device comprising, in combination with a driven element, an operating means including a movable pin, a casing on said driven element and having an aperture, a bifurcated member in the casing and having a frictional driving connection with said driven element, said casing and said member being adapted to receive said pin when said aperture and the space between the bifurcations of said member are in registering relation opposite said pin, and means for limiting the rotational movements of said casing and said bifurcated member with said driven element.

14. A machine of the character described having a safety device comprising, in com-

bination with a driven element, a stop member, operating means for said member including a slide rod, and means operatively associated with said driven element including a pair of parts normally coacting to prevent movement of said rod but adjustable when the driven element is at rest into a position to permit such movement of the rod.

15. A machine of the character described comprising, in combination, an operating device, a movable element adapted to be moved into open or closed position, means for driving said operating device, said means including a control element having an operative and an inoperative position, a stop member movable by said closure, a second stop member movable into the path of said first mentioned stop member to prevent said closure from being opened, and a third stop member operatively connected to said second stop member and adapted upon movement of said second stop member into position to permit opening of said closure to engage said control element in its inoperative position, said first mentioned stop member being mov-

able into the path of said second stop member when said closure is opened.

16. A machine of the character described having, in combination, a body having a closure, and containing an element to be driven, a stop member movable by said closure, a second stop member movable into the path of said first mentioned stop member to prevent opening of said closure, means preventing movement of said second stop member out of the path of said first mentioned stop member until said element has ceased movement, means for driving said element including a control element having an operative position and an inoperative position, and a third stop member operatively connected to and movable simultaneously with said second stop member, said third stop member being movable to engage said control element when said second stop member is moved out of the path of said first mentioned stop member.

In testimony whereof we have hereunto affixed our signatures.

ROBERT H. PALM.

WILLIAM F. POHLMANN.
